DESIGN FOR A GEAR SHIFT BALL

Frank M. Hoover, Youngstown, Ohio

Application December 22, 1937, Serial No. 73,803

Term of patent 7 years

To all whom it may concern:

Be it known that I, Frank M. Hoover, a citizen of the United States, residing at Youngstown, in the county of Mahoning and State of Ohio, have invented a new, original, and ornamental Design for Gear Shift Balls, of which the following is a specification, reference being made to the accompanying drawing, forming a part thereof, in which:

Fig. 1 is a top view of a gear shift ball showing the novel design.

Fig. 2 is a side elevational view of the gear shift ball.

Fig. 3 is a horizontal sectional view of the gear shift ball taken on the line 3—3 of Fig. 2 looking in the direction indicated by the arrows.

I claim:

The ornamental design for a gear shift ball, substantially as shown.

FRANK M. HOOVER.
